UNITED STATES PATENT OFFICE.

PHILIP JOSHUA LE SUEUR, OF BRIGHTON, ENGLAND.

ATTACHMENT TO CARPENTERS' AND SIMILAR HAND DRILLING-BRACES.

1,344,910.

Specification of Letters Patent. Patented June 29, 1920.

Application filed January 10, 1916. Serial No. 71,371.

To all whom it may concern:

Be it known that I, PHILIP JOSHUA LE SUEUR, a citizen of the United States, and a resident of Brighton, county of Sussex, 5 England, have invented a new and useful Attachment to Carpenters' and Similar Hand Drilling-Braces, of which the following is a specification.

My invention is applied to the ordinary 10 drilling brace of commerce and by a novel arrangement of parts converts a brace into a practical tool for drilling iron or other metals, the drill being forced automatically into the metal to be drilled by the rotation 15 of the brace by the hand and arm of the operator in the usual manner when using a brace.

A very valuable feature of this invention 20 enables the operator to drill holes around the top of a boiler or tank, or to drill holes around a hole in a steam boiler (which may result from a boiler explosion) and also drill holes around the edge of a plate suitable to rivet over the hole in the boiler.

An object of the invention is to provide a 25 brace that shall enable a workman to do the various kinds of work required in motor or other repairing, and that shall be available for the boring of wood as well as the drilling 30 of metal.

A special feature of the invention is the 35 facility with which the automatic arrangement for drilling iron may be thrown out of gear and preserved from injury and wear when the operator uses the brace on work common to the ordinary brace.

Another valuable feature of the invention 40 consists in the faculty with which the drills either for wood or iron may be changed, the arrangement of parts being much simpler than in the ordinary brace of commerce, thus effecting a great saving of time and lessening the cost of manufacture.

Another valuable feature of the invention 45 is the device which automatically forces the drill into the substance to be drilled requiring no pressure from the operator against the brace.

The most striking feature of this invention 50 is that a certain automatic movement which formerly went to waste, is now utilized.

Figure 1 is a perspective view of the invention showing all its main features.

55 Fig. 2 is a view of the invention as ap-

plied to an ordinary brace, showing also the method employed in drilling cylindrical bodies, and also illustrates the position of the collar for retaining the drill in the drill socket.

Fig. 3 represents a longitudinal section of the spindle portion of the attachment.

Fig. 4 represents the drill showing the projections or flanges on the shank.

Fig. 5 is an end view of the drill shank.

Fig. 6 is a perspective view of the flanged non-turnable collar.

Fig. 7 is a perspective view of the cramp-like casting with the chain attached.

Fig. 8 is an end view of the drill socket.

Fig. 9 is a longitudinal section of the hand grip of the brace, showing also the flanged collar supporting a special form of bearing pin.

Fig. 10 is a side view of the stop piece for 75 regulating the stroke of the lever.

Fig. 11 is a perspective view of an auxiliary stop piece.

Fig. 12 is a side view of a special form of bearing pin.

Fig. 13 is a view of the flanged collar showing the bearing pin placed out of gear and the ratchet wheel and ratchet.

Fig. 14 is a perspective view of a collar designed to keep the bits in rigid engagement with the drill socket.

Fig. 15 is a partial front view of the collar shown in Fig. 14.

Fig. 16 is an end view of the drill socket showing a projection designed to engage a 90 groove in the drill shank.

Fig. 17 is a longitudinal section of a special form of hand grip for the brace.

Fig. 18 is a view in elevation showing a train of gear wheels for rotating the forcing 95 screw.

Fig. 19 is a perspective view of a drill whose shank is provided with a groove also a flattened portion.

Fig. 20 is a side view of the "stop-piece" 100 with the auxiliary attachment applied.

Fig. 21 is a perspective view of the adjusting nut designed to engage the outer end of the spindle portion of the attachment.

In the drawings, 2 designates the steel 105 frame of the brace, provided at its inner end with the usual body rest 3.

The outer end of the brace is provided with an attachment 4, in which the most prominent features of the invention are em- 110

bodied, and though the ratchet device of commerce is used owing to its adaptability for drilling in corners, it is not claimed as part of the invention, for as shown in Fig. 2 5 the action of the various parts of the "attachment" are the same as when used with the ratchet device of commerce.

The attachment 4, has a reduced portion 10 5, (Fig. 3) which engages the journal hole 6 and passing through the ratchet wheel 7, it is secured thereto by a screw A. The longitudinal hole 8 receives the shank of the 15 drill 9, which is rendered non-turnable relative to the attachment 4, by the projections 15 9^A (Fig. 4) which engage the two grooves 8^A cut longitudinally in each side of the 20 hole 8.

The grooves are the preferred design for 20 rendering the drill non-turnable, as by this 25 plan the hole and the grooves may be cast. The drill shank could be grooved or flattened, and a corresponding flat part provided in the drill socket as shown in Fig. 8. Both these cases are objectionable from a 25 manufacturing standpoint as the hole could not be bored true relative to the attachment.

The attachment 4, is threaded at its outer 30 end, the nut 10, (Fig. 21) engaging the threaded portion. The flanged collar 12, 35 (detail Fig. 6) is in practice placed behind the nut 10, and is rendered non-turnable by a suitable projection 12^A, which engages with the groove 14. The reduced portion of the non-turnable collar 12 is designed to 40 receive the collar 16 of the cramp-like casting 17, (Fig. 7) which holds the article to be drilled in direct contact with the point of the drill. It will be observed that the casting 17 is provided with a semi-circular 45 bearing 16^A which works on the smooth portion of the attachment 4, relieving the flanged collar 12 of considerable strain. Said casting is also provided with a triangular slot B for drilling small round bars 50 or pipes. The said casting may be made in various forms to suit different kinds of work.

The inner portion of the attachment 4 is 50 pierced longitudinally by a hole 18 which connects with the drill shank hole 8. Said 55 hole 18 being threaded, is designed to receive the forcing bolt 20 which normally contacts with the inner end of the shank of the drill at D. Reference to the drawings shows that the drill shank is quite long and is designed to slide longitudinally in the 60 drill socket under the action of the forcing screw. The inner end of the forcing bolt 20 is provided with a large head 22 having 65 ratchet teeth on its outer periphery, also the pivot 23 projecting from the center of the ratchet wheel. The device which automatically forces the drill against the object to be drilled consists of the lever 24 pivotally 70 connected with the forcing screw 20, the

lever preferably consisting of two plates which pivotally engage the forcing screw, a plate on each side of the ratchet wheel 22. One of said plates suitably bent at E provides the space for the ratchet wheel and 75 also the space for the ratchet 25 and the ratchet spring 26, the plates joining at the bend E are riveted together and form one plate, making a strong plate and yet occupying little space. The lever extends along 75 the arm of the brace and is operated by the pin or bearing 27, which projects from the flanged collar 28 of the hand grip 30.

The utilization of the automatic motion of the hand grip is as far as I am aware, 80 novel, and while the preferred form for rotating the forcing bolt is that shown in Figs. 1 and 2, consisting of the lever and ratchet device; it is obvious that a driving pinion may be mounted on the hand grip in 85 place of a bearing pin, and a suitable train of wheels connect the hand grip with the forcing bolt, as in Fig. 18, the claims are drawn with a view to cover this method of 90 rotating the forcing bolt.

In using the brace the operator grips the hand grip 30 in the usual manner and as he turns the brace to the right, the hand grip 30 turns to the left, carrying with it the bearing pin 27 which impinges upon the 95 end of the lever 24 at F and moves it over an arc varying with the arc described by the pin 27. This movement of the lever turns the forcing screw 20, forcing the drill 100 against the object to be drilled.

In order to regulate the length of the stroke a stop piece 32 is provided consisting of stiff steel wire which is secured to the attachment 4 by the ends H (Fig. 10) of the stop piece being pushed into two holes 105 drilled in the projections 33 and secured thereto by nuts. The spring 34 secured to the end of the lever and kept in position by the projection 34^A bears on the stop piece at K and causes the lever to spring 110 up against the stop piece at M and maintain a correct position relative to its engagement with the bearing pin 27. The stop piece 32 is adjusted correctly for all ordinary sized drills, but when a very small 115 drill is used and it is desired to shorten the stroke of the lever the auxiliary stop piece 36 (Fig. 11) is clipped on to the stop piece at M. The auxiliary stop piece consists of a sheet of steel turned up with the two ends 120 slotted at N to fit into the side bars of the stop piece 32. The spring part at O clips resiliently on to the top bar of the stop piece, thus reducing the stroke of the lever and consequently the depth of the cut of the 125 drill. Other methods may be adopted but the above is the preferred form.

Another form of bearing pin 27 (Fig. 13) which is mounted on the flanged collar 28 of the hand grip 30, is provided with two 130

pivots P which work in bearings Q (Fig. 9), the pin butting against the portion of the flanged collar 28 at R, which is the correct position when operating the lever 24. A plain bearing pin screwed into the collar 28 is illustrated in Figs. 1 and 2.

As this invention is designed to be a useful help to the mechanic, the bearing pin 27 is designed to fold under the flange of the collar 28. The dotted lines in Fig. 13 show position of pin 27, which action throws the automatic drilling device out of gear and the brace can then be used as an ordinary brace.

The method of placing the bits in position is much simpler and quicker than the plan used in the ordinary brace of commerce. The projections 9^A which render the bit non-turnable relative to the socket 9 also serve the purpose of holding the bit in the socket when pulling a wood bit out of the hole bored by it. The collar 29 (Fig. 14) which screws on to the attachment 4, is provided with a hole 30^A which is the same size as the shank of the bit. The slots or grooves 30^B when turned to register with the grooves 8^A allow the bits to be inserted in the socket 9; when the collar 29 is screwed up and the slots 30^B are out of register with the said grooves 8^A, the bit is held firmly in position.

The parts in this invention are so arranged as to be protected from damage by rough usage. The lever 24 is protected by the strong arm of the brace with which it runs parallel; but it is evident that should the brace be turned backward with great force and the bearing pin 27 strike the end of the lever 24, damage might result. To avoid this I have provided the ratchet wheel 36 (Fig. 13) which is rigidly secured to the steel frame of the brace at S, serving also as one of the collars to retain the hand grip 30 in position. The ratchet 37 pivotally connected to the flanged collar 28 and secured thereto by the screw T is held in resilient contact with the ratchet wheel by the spring 38. This device prevents the hand grip 30 from being turned backward, the hand of the operator turning around the hand grip instead.

In operating the device the collar 16 of the cramp-like casting (Fig. 7) is placed on the cylindrical portion of the attachment 4. The non-turnable collar 12 is also placed in position, the collar 16 engaging the reduced portion of said collar. The nut 10 (Fig. 21) is then screwed up against the non-turnable collar 12. The metal 40 to be drilled is placed between the point of the drill and the bearing B of the cramp-like casting 17 and the nut 10 screwed up tight, the forcing bolt 20 being adjusted to drill a suitable depth. The operator then turns the brace in the usual manner. The bearing pin 27

acting on the end of the lever 24, forces the drill gradually and with little friction into the metal to be drilled.

If a deep hole is required the ratchet 25 is pressed out of gear, and the forcing bolt 20 screwed out, the nut 10 is then adjusted and another cut made. It will be noticed that a spur 17^A projects from the casting 17. This spur is provided with an adjustable chain which is placed around the object to be drilled, and holds the casting 17 and the object to be drilled, in position, relative to each other. This cramp-like casting is especially useful when a hole has to be drilled out from the center of the article. The chain ordinarily used always pulls the drill toward the center, breaking it in so doing.

For drilling holes in cylindrical bodies such as pipes, I prefer to employ for bringing such objects in contact with the drill, a U-shaped metal ribbon 44 (Fig. 2). In actual practice, it can easily be slipped between a pipe and a wall much easier than the usual chain; said ribbon provided with several holes V which engage the projecting parts X of the collar 46 enabling the operator to meet the requirements of a shorter drill.

Another form of hand-grip 48 is shown in Fig. 17 for use in doing heavy work; this form is simple to manufacture, the pin 49 is designed to slide into the hand-grip, the dotted lines showing its position when out of gear, the spring 50 holding the pin in position.

What I claim is:—

1. In a drilling brace, in combination, a brace frame, an attachment having a grooved drill socket suitably secured to the outer end of the brace frame, a drill having a suitable drill shank for engaging said drill socket, said attachment having a threaded hole extending longitudinally into the attachment from its inner end and connecting with the drill socket, a feed screw provided with a ratchet wheel engaging said threaded hole, a lever carrying ratchet mechanism suitably engaging said feed screw and the ratchet wheel, and means on the hand grip carried by the crank of the brace for engaging said lever and rotating said feed screw.

2. In a drilling brace, in combination, a brace frame, an attachment threaded at its outer end suitably secured to the outer end of the brace frame, said attachment provided with a grooved drill socket, a drill provided with a shank having projections and capable of moving longitudinally in the drill socket, a cramp-like casting having bearings at its inner end, and a work support at its outer end engaging said attachment, a collar engaging the attachment and said cramp-like casting, said collar rendered non-turnable relative to the attachment, an

adjustable retaining nut, a feed screw provided with a head having ratchet teeth on its outer periphery engaging the threaded hole in the inner end of the attachment and 5 engaging the inner end of the drill, a lever pivotally attached to the feed screw, and provided with ratchet mechanism for engaging the ratchet teeth on the head of said feed screw, a stop piece projecting from the 10 frame of the brace for adjusting the stroke of the lever, a spring for keeping the lever in position, and a bearing pin on the hand grip carried by the crank of the brace for oscillating the lever and rotating said feed 15 screw.

3. In a drilling brace, in combination, a brace frame, an attachment suitably at-

tached to the outer end of the brace frame, said attachment carrying a drill and provided with a feed screw operated by an automatic feed motion for the drill derived from the rotation of the hand grip on the crank, a collar provided with lugs engaging the said attachment, a non-turnable collar relative to the attachment engaging the collar with the lugs, an adjustable retaining nut, and a U-shaped metal ribbon work support engaging the lugs of said collar. 20 25

Dated the 20th day of December, 1915.

PHILIP JOSHUA LE SUEUR.
